REFLECTOR

Aaron L. Kotler, Glencoe, Ill., assignor to Gleason Corporation, Milwaukee, Wis., a corporation of Wisconsin

Filed Dec. 29, 1965, Ser. No. 367

Term of patent 14 years

(Cl. D72—1)

FIG. 1.

FIG. 2.

FIG. 1 is a front elevational view of a reflector showing my new design, the opposite side of said reflector being plain; and

FIG. 2 is an edge view of said reflector.

The pattern of small hexagonal elements shown in FIG. 1 is representative of a retroreflective prismatic pattern.

I claim:

The ornamental design for a reflector, substantially as shown and described.
